Attorneys

UNITED STATES PATENT OFFICE.

HERMAN P. GEISER, OF LIMA, OHIO.

FOLDABLE BARRICADE.

Application filed April 23, 1928. Serial No. 273,476.

This invention relates to barricades of the type intended more particularly for use in connection with street construction or repair work, and has for its object the provision of a device of this character which is light, durable and inexpensive in its construction and capable of being easily and quickly folded into a compact bundle for carrying or packing.

10 The invention is fully described in the following specification, and a preferred embodiment thereof illustrated in the accompanying drawings, in which,—

Figure 1 is a side elevation of the device in 15 set-up position. Fig. 2 is an enlarged end elevation of one of the cross-bar sections and its supporting leg in set-up position, with the lower portion of the leg broken away. Fig. 3 is an enlarged fragmentary top view of the 20 central jointed portion of the cross-bar. Fig. 4 is an enlarged top view of one end portion of Fig. 1. Fig. 5 is an end elevation of the lower portion of one of the legs in set-up position, and Fig. 6 is a side view of the device 25 in completely folded position.

Referring to the drawings, 1 designates the cross-bar of a barricade embodying the invention, which bar comprises two sections 1^a and 1^b, preferably of strap or flat bar metal, with 30 the inner ends of the sectionslapping in side abutting relation and connected for folding movements by a pivot 2. The inner end of one section extends a short distance beyond the pivot and terminates in a laterally projecting 35 stop tongue 3, which enters a registering notch 4 in the top of the other section when the sections are in full extended or unfolded positions, as shown in Fig. 1, thus permitting a 40 folding of the sections in only one direction from full extended position.

A leg 5, also preferably of strap or flat metal, is pivoted at its upper end to the outer end of each section of the cross-bar 1 in side lapping relation thereto, the pivot being 45 designated 6. Each leg laps the outer side of the cross-bar section to which attached and is provided at its lapping end with an inwardly projecting stop tongue 7, which, when the leg is in set-up position, engages over the top 50 of the section in a notch 8 therein, thus limiting the outward pivotal movement of the legs relative to the cross-bar.

Each leg has its lower end portion given a 55 quarter turn outwardly from the cross-bar section to which attached about an axis disposed longitudinally to the leg so that the flat

sides of the lower end portion of the leg are disposed transverse instead of longitudinally to the cross-bars. The turning of the lower portion of the leg outward with respect to the cross-bar section to which attached provides the leg with a straight inner side surface that is parallel with the outer side surface of such section to permit the leg to be folded alongside of the section, as shown in Fig. 6.

A foot-bar 9, also preferably of flat bar metal, is pivoted substantially centrally of its ends to the outer side of each leg 5 and is adapted to be placed in crosswise leg supporting position or in folded parallel lengthwise 70 relation to the leg. A bracing link 10 is pivoted at one end to the outer side of one end of the foot-bar 9 and has its upper end provided at one side with a notch 11 for engaging over a stud 12 on the outer side of the associated leg, thereby to releasably retain the leg and foot-bar 9 in set-up relation, as shown in Fig. 5. When folded, the foot-bar 9 and brace 10 lie side by side in parallel relation and the two lie in corresponding relation to the leg.

An arm 13 is pivoted to the outer side of the upper end portion of each leg 5 and is adapted to be folded alongside thereof in lengthwise relation thereto or to be swung outward from the leg in horizontal position to support a lantern or other signal device. The arm 13 is supported in horizontal usable position by a laterally projecting stud 14 on the leg.

It is apparent that when the device is folded from the set-up position shown in Fig. 1 the 90 feet 9 and braces 10 are folded in longitudinal relation to the respective legs, the legs are then each folded along the outer side of the cross-bar section to which attached and the cross-bar sections are then folded so as to place the parts in complete folded relation 95 shown in Fig. 6. The arms 13 are also folded alongside of the legs longitudinally thereof.

I wish it understood that my invention is not limited to any specific construction, arrangement or form of the parts, as it is capable of numerous modifications and changes without departing from the spirit of the claims.

Having thus described my invention, what I claim as new and desire to secure by Letters 105 Patent is:—

1. In a device of the character described, a cross-bar, supporting legs for the cross-bar foldable along opposite sides thereof, a foot-bar foldably attached to the lower end of each leg in transverse relation to the cross-bar and adapted to be swung into lengthwise rela-

tion to the leg, and means for releasably holding the foot-bar in set-up relation to the leg.

2. In a device of the class described, a cross-bar, a leg pivoted to each end of the cross-bar to be folded alongside thereof in parallel relation thereto and having stop coaction with the cross-bar to limit its unfolding movement relative thereto, a foot-bar pivoted in spaced relation to its ends to the lower end of each leg to be folded along a side of the leg in lengthwise relation thereto, and a brace member releasably connecting each foot-bar to its leg to retain the same in set-up relation and adapted to be placed in lengthwise relation to the leg and foot-bar when in folded position.

3. In a device of the class described, a cross-bar, a leg pivoted at its upper end to each end of the cross-bar with such legs disposed at opposite sides of the cross-bar to be swung in lengthwise relation along the respective sides of the cross-bar and having its outward swinging movement relative to the cross-bar limited, means at the lower end of the leg forming a foot therefor and adapted to be placed in leg supporting position or in compact folded relation thereto, said cross-bar having provision permitting a folding thereof to shorten its length when the device is folded.

4. A cross-bar, legs pivoted to opposite ends of the cross-bar in lapping relation to opposite sides thereof and adapted to be folded along the respective side of the cross-bar in longitudinal relation thereto, said legs also having provision for limiting the outward swinging movements thereof relative to the cross-bar, a foot-bar pivoted to the lower end of each leg to adapt it to be disposed in leg supporting position crosswise of the cross-bar or to be placed in longitudinal relation to the leg at the outer side thereof relative to the cross-bar, and means for securing the foot-bar in set-up relation to the leg, said cross-bar being jointed to permit a folding of the same to shortened form.

5. In a device of the class described, a cross-bar comprising sections of flat metal having their inner ends pivotally connected in lap-

ping relation and provided with stop means for limiting the unfolding movements of the sections, legs pivoted at their upper ends to the outer ends of respective sections of the cross-bar at the outer sides thereof and adapted to be placed alongside the respective section in longitudinal relation thereto and having provision for limiting their unfolding movements relative to the sections, a foot-bar pivoted in spaced relation to its ends to the lower end of each leg to be placed in leg supporting position crosswise of the crossbar or in folded position alongside of the leg in longitudinal relation thereto at the outer side thereof with respect to the cross-bar section to which the leg is attached, and means foldable with respect to the leg and foot-bar for releasably retaining them in set-up relation.

6. In a device of the class described, a cross-bar having sections of flat metal pivoted together in lapping relation at their inner ends to permit a folding thereof and having provision for limiting the unfolding movements thereof, a leg pivoted at its inner end to the free end of each of said sections in lapping relation to the outer side thereof and having stop coaction with the section to limit the relative unfolding movements of the leg, said legs adapted to be folded alongside of the respective section in longitudinal relation thereto and being of flat metal with the lower end thereof formed with a quarter turn about the longitudinal axis of the leg and outward from the outer side of the cross-bar section to which attached, a foot-bar pivoted to the outer side of each leg at its lower end transverse to the cross-bar and adapted to be placed in folded relation longitudinally of the leg, a brace-link connected to each leg and its foot-bar to releasably retain them in set-up relation and adapted to be folded therewith into longitudinal relation to each other, and an arm foldably connected to each leg and adapted to support a signal device.

In testimony whereof I have hereunto signed this specification.

HERMAN P. GEISER.
